UNITED STATES PATENT OFFICE.

LUCKEY D. LONG, OF BRONSON, KANSAS.

HEAD-LAMP.

1,209,600.

Specification of Letters Patent. Patented Dec. 19, 1916.

Application filed July 2, 1915. Serial No. 37,732.

To all whom it may concern:

Be it known that I, LUCKEY D. LONG, a citizen of the United States, residing at Bronson, in the county of Bourbon and 5 State of Kansas, have invented new and useful Improvements in Head-Lamps, of which the following is a specification.

This invention relates to headlamps such as are now commonly used upon automobiles and similar vehicles for the purpose of illuminating the road way at night time, the 10 object of the present invention being to construct the headlamp in such manner that in addition to the means for projecting the rays 15 of light in advance of the machine, said head lamp is provided with a side window or light and in connection therewith a reflector arranged at the opposite side of the burner whereby both sides of the road way may 20 be also illuminated thus avoiding danger in turning the machine to one side or the other.

A further object of the invention is to provide a novel mounting for the main reflector arranged behind the burner, whereby said reflector may be adjusted to either direct the rays of light downwardly, upwardly or in 25 a substantially horizontal plane as may suit the convenience of the driver of the machine and also to enable him to comply with varying traffic regulations especially in large 30 cities.

With the above and other objects in view, the invention consists in the novel construction, combination and arrangement of parts, 35 as herein described, illustrated and claimed.

In the accompanying drawings:—Figure 1 is a side elevation of a headlamp embodying the present invention. Fig. 2 is a vertical cross section through the same on the 40 line 2—2 of Fig. 1. Fig. 3 is a central vertical fore and aft section through the lamp.

Referring to the drawings 1 designates the body of the lamp which in the main is of the ordinary construction now in common use, 45 the same being provided with the head panel or lens 2 arranged in front of the burner 3 for illuminating the road in advance of the vehicle by which the lamp is carried.

50 In carrying out this invention, in addition to the panel or lens 2 at the front of the lamp, the body of the lamp is formed with an opening 4 in the outer side thereof which is covered by a panel 5 of glass and at the

opposite side of the burner 3, a reflector 4^a 55 is secured to the inside of the body of the lamp, the reflector 4^a acting in the same capacity and performing the same function as the ordinary main reflector located in rear of the burner.

The main reflector indicated at 6 is provided with a backwardly extending threaded stem 7 while the body or frame of the lamp is formed with an upwardly and downwardly extending slot 8 in which the stem 7 is adjustable, the stem 7 having a clamping nut 9 thereon so that by loosening the nut 9, the stem together with the main reflector 6 may be slid upwardly or downwardly with the obvious result that the rays of light reflected therefrom will be projected in an upward or downward direction or straight ahead in a substantially horizontal plane as may be found expedient or necessary at the time. The side panel of glass 5 is preferably 75 mounted in and carried by a door 10 which is hinged at 11 and ordinarily held close by means of a catch or fastener 12 opposite the hinge 11. Thus the door 10 may be used for the purpose of lighting or extinguishing the 80 burner without necessitating the opening of the front lens 2 or the door carrying said lens.

What I claim is:—

In a headlamp of the class described, a 85 lamp body embodying a vertically curvilinear rear wall formed with a vertically extending slot, a translucent front panel, a main reflector arranged within the body of the lamp and adjacent to said rear wall, a 90 threaded stem projecting rearwardly from said reflector and movable lengthwise of said slot, a clamping nut on said stem located exteriorly of said rear wall, whereby said main reflector may be adjusted from the outside of the body upwardly or downwardly 95 to project the rays of light at a corresponding angle, a hinged door at the outer side of the body, a translucent panel in said door, and a second reflector within the lamp body 100 opposite said door.

In testimony whereof I affix my signature in presence of two witnesses.

LUCKEY D. LONG.
